ANTONIO ARCADU, OF PEEKSKILL, NEW YORK.

CHICKEN COOP.

Application filed July 11, 1924. Serial No. 725,372.

This invention relates to chicken coops, and has for its object a combination of devices that will enable one to maintain a coop in a healthful and sanitary condition both for the fowls housed therein and for the people who have to be near to them. The object is attained through the means set forth in this specification and the accompanying drawings, in both of which like letters refer to similar parts in the several figures, and their description.

Referring to the drawings, Fig. 1 is a side elevation of the features of the invention, showing a movable platform to be in its normal place. Fig. 2 is a side elevation of the same features with the movable platform shown outside of the coop. Fig. 3 is a plan of the devices in position as in Fig. 2. Fig. 4 is an enlarged transverse sectional view 20 of the platform supports. Fig. 5 is a like presentation of the supports for the perch.

Figs. 1, 2, 3 represent a wall *y* which will be considered as the outside wall of the coop, to the left of the wall the inside and 25 to the right of the wall the outside of the coop. Preferably upon a framed standard, as at *r*, that may be of any desirable length and width, a perch or perches, as *p'*, are erected. Upon the ends of the standard are 30 track bars *t*, which may be angle bars of iron or steel. A platform *l* about covering the standard is provided with flanged wheels *n* to traverse the tracks *t*. The said tracks are given an inclination from the inner side 35 of the standard to the track support *u* outside of the coop. At the extreme outer ends of the tracks they are given an upward turn *v*, to serve as a check to the platform, as in Fig. 2. The inclination of the tracks is 40 given to admit of the platform descending by gravity from the position shown in Fig. 1 to that in Fig. 2.

Upon the inner side of the standard *r*, Fig. 3, are bearings *n'* *n'* that support a 45 shaft *m*. One end of the shaft is made to receive a crank *D*, and midway of the bearings is a winding drum *m'*. To the drum one end of a flexible fabric or metallic belt or strap *p* is secured and the other end 50 of the strap is attached to the front axle under the platform *l*, as at *p''*, Fig. 3. A reason will be stated for not attaching the strap directly to the platform. By these means, turning the crank in one direction 55 allows the platform to glide down the in-

clined tracks to the outside of the coop, as in Figs. 2 and 3, turning the crank the other way draws the platform into the interior of the coop, as in Fig. 1.

Upon the inside of the wall *y*, or to any 60 equally convenient fixture, hangers *n* *n* are secured to support a shaft *m'*. At one end of the shaft is an arm *e'* and at the other end is an arm *1°*. Connecting these arms is a curved plate *f*, so that when the shaft is 65 turned the plate moves with the arms that are fast on the shaft. An upward extension *e* of the arm *1°* provides for pivoting to it of a handle arm *i*, Figs. 1, 2 and 3, that extends towards and near to the crank 70 end of the shaft *m*, so it can be manipulated by an operator at the crank. In the under side of the arm are notches *j* that are adapted to engage with a bracket *i'* conveniently located. Lifting and pulling the arm *i* 75 causes the lifting of the ends of the arms *e'* and *1°*, and lifting and pushing the arm *i* causes a lowering of those arms.

Upon the crank end of the shaft *m* is a sprocket wheel *g*. Upon the outer end of 80 the shaft *m'* a spur wheel *c* and a sprocket wheel *d* are fast together and turn on the shaft *m'*. The arms *e'* and *1°* are provided with bearings as *e''* in the arm *e'*, Fig. 3, (the bearing in the arm *1°* corresponding 85 with the bearing in the arm *e'*) which support a brush shaft *m''*. Upon the shaft *m''* is a brush *a* that is a trifle longer than the length of the platform *l*, and upon the outer end of the brush shaft is a pinion *b* which 90 engages with the spur wheel *c*. The sprocket wheels *g* and *d* are connected by a sprocket chain *h*. Turning the crank *D* revolves the brush *a*.

The object of the brush *a* is to clean off 95 the platform *l*, in this way: When the platform is to be cleaned the crank *D* is to be used to allow the platform to roll out upon its tracks. When the movement of the crank is reversed to pull the platform back 100 the brush is first lowered as in Fig. 2 by means of the notched arm *i*, and then as the platform is drawn forward, the brush, revolving in the direction of the arrow *B* in Fig. 2, brushes off the surface of the platform.

Hinged to the plate *f* is an apron *f'* that serves to confine the sweepings from the platform within limits, and the lower edge of the apron can be made to scrape away 110

whatever cannot be removed by the brush. Below the brush, under the tracks, is a removable receptacle *w* for catching the sweepings from the platform. The front *s* of the receptacle is adapted to be opened for the removal of the brushings.

As the object of these combinations is to maintain sanitary conditions in a coop, means are provided for keeping vermin from the fowls so far as possible. To that end the perches, as *p*', are mounted above the platform that becomes the floor beneath the perch, upon standards *s'* *s'* that arch from the frame. The tops of the standards are provided with cups *c' c'* that are shown in enlarged detail in Fig. 5. From the inner bottom of the cup *c'* is a projecting stem *c''*. The perch is perforated on its under side to receive said stem. The perches are made removable from the stems for the purpose of cleansing them. Some kind of liquid or light oil is to be put in the cups which will prevent vermin from creeping from the standards to the perch.

Likewise the movable platform *l* is mounted upon the stems in the cups *o* that are secured to the chassis under the platform. The reason for attaching the strap *p* to the axle or the chassis instead of to the platform, is to prevent the passage of vermin from the parts under the platform to the platform.

Summarized, the combination may be described as a movable floor under the perch or perches, on an inclined track, with a crank shaft and belt means for controlling the movements of the floor, and a brush suspended above the floor adapted to be tilted up from contact with the floor or down to contact with the floor, and belted means from the said crank shaft to gearing on the tilting frame for revolving the brush while the floor is being moved, with means for concentrating the brushings from the floor into a receptacle, and means to protect the floor and perches from vermin.

Having described my invention, what I

claim and desire to obtain by Letters Patent, is—

1. In a chicken coop the combination of a standard, a movable floor under the perch, a track on the standard upon which the floor moves, a crank shaft, a drum on the crank shaft and a flexible connection of the drum with the movable floor, a revolving brush contiguous to the movable floor, a tiltable frame supporting the brush, a shaft supporting the tiltable frame, fixed bearings for said shaft, a united sprocket wheel and spur wheel having bearings on the end of said shaft, a gear pinion on the brush shaft engaging with the said spur wheel, and the said sprocket wheel belted to a sprocket wheel on said crank shaft.

2. In a chicken coop the combination of a standard, a track on the standard and a movable floor on the track under the perch, the track inclined so that the floor will move in one direction by gravity, a crank shaft, a drum and strap means for pulling the floor one way, a revolving brush contiguous with the movable floor, a tilting frame to support the brush, a shaft in fixed bearings supporting the tilting frame, a united spur and sprocket wheel having on said shaft, a pinion on the brush shaft engaging with said spur wheel, a hinged apron on said tilting frame, a receptacle to receive brushings from the movable floor, a perch above the normal place of the floor, said perch and floor supported upon means to keep away vermin.

3. In a chicken coop as described the combination with a movable table of a revolvable brush in a tiltable frame supporting the brush, coating means for simultaneously operating the table and the brush, and a handle arm notched to engage with a fixed stop and pivoted to an arm on the tiltable frame for actuating the said frame.

In testimony whereof I have affixed my signature.

ANTONIO ARCADU.
